UNITED STATES PATENT OFFICE.

WILLIAM G. BIRD, OF KANSAS CITY, KANSAS, ASSIGNOR TO JACOB C. DOLD,
OF KANSAS CITY, MISSOURI.

HYDROCARBON-LAMP.

SPECIFICATION forming part of Letters Patent No. 655,188, dated August 7, 1900.

Application filed February 26, 1900. Serial No. 6,558. (No model.)

To all whom it may concern:

Be it known that I, WILLIAM G. BIRD, a citizen of the United States, and a resident of Kansas City, Wyandotte county, Kansas, 5 have invented certain new and useful Improvements in Hydrocarbon-Lamps, of which the following is a specification.

My invention relates to improvements in hydrocarbon-vapor-burning lamps for illuminating purposes, and especially to the form, location, and construction of the vaporizing-tube and mixing tube or chamber. I conduct the hydrocarbon from the tank or reservoir to a vaporizing-tube exposed to the 15 heat of the burner of the lamp, in which tube said liquid is vaporized and from which it is projected in the form of a jet into a mixing-tube and gas-supply tube leading from such mixing-tube to the burner of the lamp. I 20 provide novel means for dividing or distributing the liquid in the vaporizing-tube and an improved metal canopy or drum to be placed over the lamp-chimney, inclosing the terminal portion of the vaporizing-tube to secure 25 greater concentration of heat upon said tube.

In the drawings, Figure 1 is an elevation of the lamp with all its parts in place. Fig. 2 is an enlarged view, partially in section, of the vaporizing-tube and nozzle detached. Fig. 3 is a detached view of a polygonal bar inserted within the bore of the vaporizing-tube. Said figure also shows a section of said bar. Fig. 4 is a central longitudinal section of the adjustable mixing-tube. Fig. 5 is a detached 35 view of a canopy or drum mounted over the burner and inclosing the bend of the vaporizing-tube. Fig. 6 is an elevation, partially in section, of a double lamp constructed on the same principle.

40 The lamp is provided with the usual elevated reservoir or tank 1, from which depends the substantially-vertical supply-pipe 2, which extends downward to a T 3, having an opening at the bottom, which is normally closed by a removable screw-plug 4. The burner 5 is mounted on the lower end of a substantially U-shaped tubular bracket 6, consisting of an upper and lower portion connected by a union 7, which is attached to the T 3 by screw-threads or in any preferred manner, but has 45 no internal communication with it.

The burner 5 is of an ordinary type of vapor-burner and is provided with the usual mantle 8 and glass chimney 9.

The vertical supply-pipe 2 is provided at a 55 suitable point above the plane at the top of the lamp-chimney with a T 10, from which extends laterally toward the lamp the vaporizing-tube 11, the admission of the liquid to which is controlled by a valve 12. Said vaporizing-tube 11 is provided at a point immediately over the burner 5 with a downwardly-curving gooseneck portion 13, which is threaded at its upper end into the tube 11 and at its lower end into a horizontally-disposed nozzle 14, lying in the vertical plane of the tube 11 and burner 5 and having a gas-orifice 14^a at its outer end. The tubular bracket 6 forms the supply-tube for supplying gas to the burner, and its upper end is curved toward 60 and terminates immediately opposite and in alignment with the nozzle 14, so that gas issuing from said nozzle will be projected directly into the tube 6.

The vaporizing-tube 11, as shown in Figs. 2 75 and 3, is provided with a removable polygonal bar or core 15, which is inserted within the bore of said tube, with its angles preferably in contact with the inner walls of the tube. The function of said bar is to divide the 80 stream of hydrocarbon coming from the reservoir and passing through said tube, the liquid passing through the spaces between the sides of the bar and the walls of the tube, thereby greatly promoting and expediting 85 vaporization. Said bar 15 is shown hexagonal in the drawings; but it is obvious that it may have any preferred number of angles. Another advantage of this construction of the vaporizing-tube is the great convenience of 90 cleaning it, the bar being easily removable for that purpose.

The gooseneck portion 13 of the tube when in operation is inclosed within an adjustable removable cylindrical drum or canopy 16, 95 open at its top and bottom and mounted on said gooseneck above the burner and inclosing at its lower end the top of the chimney. Said drum is made in two parts or sections 17 18, Fig. 1, pivoted together at 19 and provided with notches 20 21, cut in their edges upon one side of the drum, the upper ones

20 adapted to fit over and inclose the tube 11 and the lower ones 21 to engage an annular groove 22 in the nozzle 14, making tight joints. The effect of this construction is in operation 5 to subject the gooseneck 13 to intense heat, which heat is also conducted to the tube 11 and bar 15 therein, effectually vaporizing all the hydrocarbon passing through said tube. The hydrostatic pressure on the liquid in 10 pipe 2 and tube 11 causes the hydrocarbon gas to be projected from the nozzle 14 into the upper end of the gas-supply tube 6, leading to the burner 5. On the upper end of 15 said last-mentioned tube is mounted an adjustable mixing-tube 23, (shown in section in Fig. 4,) which fits over the end of tube 6 and is movable thereon. It is somewhat reduced in size at its other end, so as to fit over the end of nozzle 14, and openings 24 are provided in the walls of the mixing-tube. The 20 function of the mixing-tube 23 is to provide means of mixing a suitable quantity of oxygen from the air with the jet of hydrocarbon gas issuing from nozzle 14. If the tube is 25 made to engage both the supply-pipe 6 and the nozzle 14, as seen on the right-hand side of Fig. 6, the amount of oxygen passing into tubes 23 and 6 will be limited to what enters through the openings 24; but if said 30 tube 23 is disengaged from the nozzle the amount of oxygen mixing with the hydrocarbon vapor in the tube will be largely increased. The tube 23 therefore furnishes means for combining such an amount of oxygen with 35 the vapor as will secure the best practical results at the burner.

The operation has been substantially indicated. The initial heat is obtained, preferably, by applying an alcohol-torch to the 40 gooseneck 13, within the drum 16. As soon as said gooseneck and tube 11 are sufficiently heated the hydrocarbon is admitted through the valve 12, becomes vaporized, as described, and passes from nozzle 14 through the mixing-tube 23 into supply-tube 6 and thence to 45 the burner 5, where it is lighted as soon as the flow of gas is established. The torch may then be removed, and thereafter the burner furnishes the heat necessary for vaporizing 50 the hydrocarbon.

The extension 2^a of pipe 2 and the chamber in the T 3 furnish a reservoir or trap for the accumulation of any sediment or impurities contained in the hydrocarbon. Instead 55 of passing into the vaporizing-tube 11 such matters naturally settle by gravitation into pipe 2^a and said chamber. By occasionally removing the plug 4 and allowing the liquid from the tank to pass out of the opening said 60 pipe and chamber may be thoroughly flushed. Fig. 6 shows the same construction applied to a double lamp, but needs no special description.

It will be further observed that in the bore 65 of the horizontally-disposed nozzle 14 I have provided concavo-convex recesses 14^b and 14^c,

adapted to arrest atoms of dust or other impurities from passing to the supply-tube 6 with the newly-generated gases.

Having described my invention, I claim as 70 new and desire to secure by Letters Patent—

1. A hydrocarbon-lamp comprising a tank, a supply-pipe leading therefrom, a burner, a vaporizing-tube extending laterally from said supply-pipe toward the burner, a polygonal 75 bar of uniform diameter throughout its length within said tube, having its angles in contact with the walls of said tube, a gooseneck attached to the outer end of said tube, immediately above the burner, a nozzle at the end 80 of said gooseneck, having a gas-orifice in its end, a gas-supply tube having its upper end opposite said orifice and leading to the burner, and an adjustable mixing-tube normally mounted on the upper end of said gas- 85 supply tube and adapted to engage the outer end of said nozzle and form a connection between said tube and nozzle; substantially as set forth.

2. A hydrocarbon-lamp comprising a tank, 90 a supply-pipe leading therefrom, a burner, a vaporizing-tube extending laterally from said supply-pipe toward the burner, a gooseneck attached to the outer end of said tube, above the burner, a cylindrical metallic drum 95 mounted on and inclosing said gooseneck, a nozzle at the end of said gooseneck, having a gas-orifice in its end, a gas-supply tube, having its upper end opposite said orifice, and leading to the burner, and a mixing-tube normally mounted on the upper end of said gas- 100 supply tube, and adapted to engage the outer end of said nozzle, and form a connection between said tube and nozzle, substantially as set forth. 105

3. A hydrocarbon-lamp comprising a tank, a supply-pipe leading therefrom, a burner, a vaporizing-tube extending from said supply-pipe toward the burner, a gooseneck attached to the outer end of said tube, above the 110 burner, a metallic heating-drum mounted on and inclosing said gooseneck, said drum consisting of two sections adjustably pivoted together and provided with notches in their edges, to engage said vaporizing-tube and 115 gooseneck, a nozzle at the end of said gooseneck, having a jet-orifice in its end, a gas-supply tube having its upper end opposite 120 said orifice, and leading to the burner, and an adjustable mixing-tube normally mounted on the upper end of said gas-supply tube, and adapted to engage the outer end of said nozzle and form a connection between said tube and nozzle, substantially as set forth. 125

4. A hydrocarbon-lamp comprising a tank, 125 a supply-pipe leading therefrom, a burner, a vaporizing-tube extending from said supply-pipe toward the burner, a gooseneck attached to the outer end of said tube, above the burner, a metallic heating-drum mounted on 130 and inclosing said gooseneck, said drum consisting of two sections adjustably pivoted to-

gether and provided with notches in their edges, to engage said vaporizing - tube and gooseneck, a nozzle at the end of said gooseneck, having a jet-orifice in its end, provided
5 with concavo-convex recessed bore through which the gases pass to a suitable tube leading to the burner, substantially as described.

In testimony whereof I affix my signature in the presence of two witnesses.
